Primary Examiner — John A Voytek(74) *Attorney, Agent, or Firm* — QuickPatents, LLC;
Kevin Prince(57) **CLAIM**

The ornamental design for a medallion, as shown and described.

DESCRIPTION

FIG. 1 is a perspective view of a medallion, showing my new design;

FIG. 2 is a top plan view thereof;

FIG. 3 is a front elevational view thereof, the rear elevational view, left-side elevational view, and right-side elevational view all being identical thereto; and,

FIG. 4 is a cross-sectional view thereof, taken along line 4—4 of FIG. 2.

The broken lines showing a roman numeral in the figures depicts portions of the medallion that form no part of the claimed design. The bottom plan view forms no part of the claimed design.
